US00D928810S

(12) **United States Design Patent** (10) **Patent No.:** **US D928,810 S**
Hubbard et al. (45) **Date of Patent:** **** Aug. 24, 2021**

(54) **DISPLAY SCREEN WITH GRAPHICAL USER INTERFACE**(71) Applicant: **Wells Fargo Bank, N.A.**, San Francisco, CA (US)(72) Inventors: **Stephen G. Hubbard**, Chesterfield, MO (US); **Ian Keith MacEachern**, St. Louis, MO (US); **Jason Matthew Couture**, St. Louis, MO (US); **Kurt Loreck**, Caseyville, IL (US)(73) Assignee: **Wells Fargo Bank, N.A.**, San Francisco, CA (US)(**) Term: **15 Years**(21) Appl. No.: **29/748,685**(22) Filed: **Aug. 31, 2020****Related U.S. Application Data**

(62) Division of application No. 29/615,828, filed on Aug. 31, 2017, now Pat. No. Des. 896,818.

Primary Examiner — Karen E Kearney*Assistant Examiner* — Ian F Whitmore(74) *Attorney, Agent, or Firm* — Schwegman Lundberg & Woessner, P.A.(57) **CLAIM**

The ornamental design for a display screen with graphical user interface, as shown and described.

DESCRIPTION

FIG. 1 is a front view of one embodiment of a display screen with graphical user interface; and, FIG. 2 is a front view of a second embodiment thereof. The outer broken-line perimeter illustrates a display screen and forms no part of the claimed design. The remaining broken lines illustrate portions of the graphical user interface and form no part of the claimed design.

1 Claim, 2 Drawing Sheets(56)
